ATTORNEY.

UNITED STATES PATENT OFFICE.

JOHN MOON, OF NEW LONDON, CONNECTICUT.

DESIGN FOR A CUTTER AND SWAGE.

SPECIFICATION forming part of Design No. 28,425, dated March 29, 1898.

Application filed January 24, 1898. Serial No. 667,824. Term of patent 7 years.

To all whom it may concern:

Be it known that I, JOHN MOON, a citizen of the United States, residing in the city and county of New London and State of Connecticut, cut, have invented and produced a new and original Design for a Combined Cutter and Swage, of which the following is a specification, reference being had to the accompanying drawings, forming a part thereof.

10 Figure 1 is a perspective view of a combined cutter and swage, showing my new design; and Fig. 2 is a plan view of the same.

The leading or material feature of my design consists of a rectangular figure having 15 in one end thereof depressions at the center and corners and having rising from the opposite end a figure that is rectangular at the base and semicircular at its top, the described depressions being so arranged that they radiate from the center of the field in which they are disposed. Extending downward from the main rectangular figure is a smaller rectangular figure of block form that is located 20 beneath the described figure with the semi-circular top.

Referring particularly to the drawings, the letter *a* indicates a rectangular figure having in one end depressions *b*, *b'*, and *b''*, the depressions *b'* *b''* being located at the corners of said figure and extending toward the center 30 thereof. The depression *b* is located midway the depressions *b'* *b''* and also extends toward the same central point. At the opposite end of the said rectangular figure *a* is an upwardly-projecting figure *c*, that is rectangular at its base and terminates at its top in a semicircle *c'*.

d indicates a rectangular figure of block form extending downward from the figure *a*, immediately below the figure *c*. 40

Having described my invention, what I claim, and wish to secure by Letters Patent, is—

The design for a combined cutter and swage, as herein shown and described.

JOHN MOON.
